UNITED STATES PATENT OFFICE.

ELLA A. BLAKSLEE, OF ROCK ISLAND, ILLINOIS.

DESIGN FOR A STOVE.

SPECIFICATION forming part of Design No. 24,460, dated July 2, 1895.

Application filed May 2, 1895, Serial No. 547,038. Term of patent 7 years.

To all whom it may concern:

Be it known that I, ELLA A. BLAKSLEE, a citizen of the United States, residing at Rock Island, in the county of Rock Island and State of Illinois, have invented and produced a new and original Design for Cook-Stoves and Ranges, of which the following is a specification, reference being had to the accompanying drawing, showing a part thereof.

The figure is a side elevation of a range, showing my design.

The leading feature of my design is the raised ornamentation shown in the drawing, consisting of the fantastic figures of the style of ornamentation known and called the "German Renaissance," and appearing in different arrangement on the various parts of the range or stove.

The range or stove rests upon the standard S, upon which the ornamentation extends from each end toward the center. Each leg L of the stove is ornamented in the same style, as shown.

The oven-door O occupies the greater portion of one side of the stove or range. It is oblong in its general contour, its lower half being a little longer and extending farther to the front than its upper half, and its front edge slopes backward. Its outer edge is beaded, except at the bottom. At the front near the edge of the lower elongated half is borne the ornamented handle h. Near the center of the door is a medallion m. In front of the medallion is a conventionalized group of floral designs. Encircling the medallion is ornamentation of the same conventionalized design, somewhat resembling a wreath. The rest R, below the oven-door, has its outer edge scalloped. The reservoir C, in the rear of the oven-door, is ornamented with a modification of the same design.

The side door of the fire-box and so much of the body of the stove as is in front of the oven-door is ornamented with a modification of the same design, as shown. The high closet or warming-oven A is ornamented in the same general style.

The standard B and the ornamental guard or back of the high closet D have each near its center an ornamented shell design appropriately surrounded by designs in harmony with the general style of the stove or range, as shown. At top and bottom of the high closet are borne ornamented flanges a a, scalloped as shown.

The general outline of the body of the stove or range is rectangular. The reservoir, which slopes upward at the bottom to the rear, is attached to the rear of the stove. The hearth extends outward in front, as shown.

The general contour of the stove and the appearance of its ornamentation are the same in the range and cook-stove.

Having thus described my invention, what I claim as new, and desire to secure by Letters Patent, is—

1. The design for a stove herein set forth and shown.
2. In the design for a cook-stove herein set forth and shown, the design for an oven door set forth and shown.
3. In the design for a cook-stove herein set forth and shown, the design for standard and legs set forth and shown.
4. In the design for a cook-stove herein set forth and shown, the design for a reservoir set forth and shown.

ELLA A. BLAKSLEE.
